DESIGN FOR A RACK OR THE LIKE FOR
BILLIARD CUES

Donald Deskey, New York, N. Y., assignor to
The Brunswick-Balke-Collender Company,
Chicago, Ill., a corporation of Delaware

Application September 20, 1947, Serial No. 141,509

Term of patent 14 years

(Cl. D34—3)

To all whom it may concern:

Be it known that I, Donald Deskey, a citizen of the United States, residing in the city of New York, in the county of New York, State of New York, have invented a new, original, and ornamental Design for a Rack or the Like for Billiard Cues, of which the following is a specification, reference being had to the accompanying drawings, forming a part thereof.

Fig. 1 is a front perspective view of a rack or the like for billiard cues, showing my new design; Fig. 2 is a side elevational view thereof on an enlarged scale;

Fig. 3 is a top plan view on the enlarged scale; Fig. 4 is a bottom view on the enlarged scale.

I claim:

The ornamental design for a rack or the like for billiard cues, as shown.

DONALD DESKEY.
